DESIGN FOR A TEXTILE FABRIC

Michael Cembalest, New York, N. Y.

Application April 12, 1940, Serial No. 91,624

Term of patent 3½ years

To all whom it may concern:

Be it known that I, Michael Cembalest, a citizen of the United States and residing at New York city, in the county of New York and State of New York, have invented a new, original, and ornamental Design for a Textile Fabric, of which the following is a specification, reference being had to the accompanying drawing, forming part hereof, and in which the figure shows a plan view of a textile fabric showing my new design.

I claim:

The ornamental design for a textile fabric, substantially as shown.

MICHAEL CEMBALEST.
